C. E. BOILLOT.
SELF WINDING CLOCK MECHANISM.
APPLICATION FILED JULY 12, 1919.

1,416,254.

Patented May 16, 1922.

UNITED STATES PATENT OFFICE.

CHARLES E. BOILLOT, OF BROOKLYN, NEW YORK.

SELF-WINDING CLOCK MECHANISM.

1,416,254.

Specification of Letters Patent. Patented May 16, 1922.

Application filed July 12, 1919. Serial No. 310,389.

To all whom it may concern:

Be it known that I, CHARLES E. BOILLOT, residing at Brooklyn, in the county of Kings and State of New York, have invented certain new and useful Improvements in Self-Winding Clock Mechanism, of which the following is a specification.

This invention relates to self-winding clocks, and one of the objects of the invention is to provide new and improved means whereby a clock will automatically wind itself at predetermined intervals.

A further object of the invention is to provide a construction such that the operation of the self-winding mechanism is substantially noiseless.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claim.

In the accompanying drawings, wherein I have illustrated a preferred form of embodiment of my invention:

Figure 1 is an elevational view of a portion of a clock mechanism equipped with my invention.

Figure 2 is a similar view showing the opposite side of the mechanism from that illustrated in Figure 1; and

Figure 3 is an end elevational view showing the manner of supporting the operating electro magnet.

Referring now to the drawings, wherein similar reference characters refer to similar parts throughout the several views thereof, the reference numeral 1 denotes the casing of a clock, and 2 denotes a wall which is carried interiorly of the casing 1 of the clock. 3 denotes a frame, which is suitably carried by the wall 2, being mounted thereon as by means of the screws 4. 5 denotes generally the clock-work mechanism which need not be specifically described, inasmuch as that shown is of the conventional type. It consists of the usual escapement mechanism 6, balance wheel 7, the gear wheel 8, to the shaft 9 of which may be attached one of the hands of the clock, all of said chain of mechanism being driven by the main spring 10, one end of which is connected with the gear wheel 11, and the other with a fixed

support; the gear wheel 11 meshing with a gear wheel 12 (shown in dotted lines in Figure 2) mounted upon the shaft 13 of the ratchet wheel 14.

It will be understood that when ratchet 14 is rotated in a counter-clockwise direction, the gear wheel 13 will be rotated to wind up the main spring 10, and that thereafter said spring, through the chain of connected mechanism, will operate the hands of the clock.

Journalled upon the shaft 13 of the ratchet wheel 12, is a lever 15, and near the upper part of this lever is provided a pawl 16, spring-pressed into engagement with the teeth 17 of the ratchet wheel 14, as by means of the spring 18. Pivotaly connected with the upper end of the lever 15, at 19, is a link 20, the opposite end of which is pivotally connected at 21 with an arm 22 fixedly mounted upon the shaft 23, which shaft has also fixed thereto armatures, one of which is shown at 24. The armatures 24 have the arc-shaped heads 25, which co-operate with the cores 26 of the electromagnets 27 and 28. These electromagnets are supported as by means of a bracket 29, carried upon the frame 3. The ends of the cores 26 are formed upon the arc of a circle, as shown at 30, which arc corresponds with the arc-shaped heads 25 of the armatures 24.

Thus it will be seen that when the electromagnets 27 are energized, the armatures 24 will be swung toward the cores, whereby the arm 22, through its connection with the link 20, will swing the lever 15, whereby the pawl 16 will rotate the ratchet wheel 14, thereby winding up the main spring. A retrograde movement of the ratchet wheel 14 is prevented, as by means of the spring-pressed pawl 31.

Mounted upon the shaft 32 of the gear wheel 11, and fixed thereto, is a wheel or disk 33, upon the periphery of which is adapted to bear the free end of a brush 34, the latter consisting of a spring carried upon a block 35, formed of insulating material, said block being suitably mounted upon the frame 3.

Extending through a block 36, formed of insulating material, likewise carried upon the frame 3, is a screw-threaded contact member 37, the latter being threaded into the block so that the same may be adjusted, whereby the position of the contact point 38 may be varied at will.

The contact point 38 co-operates with contact point 39, carried upon the free end of the arm 40, the opposite end of which is carried by the arm 22.

5 Thus it will be seen that when the electromagnets 27 are energized, drawing the heads 25 of the armatures 24 toward the cores 26, the contact points 38 and 39 will be separated, which operation, as hereinafter described, will break the circuit through the electromagnets 27, whereby the armatures 24 will fall by gravity and again engaging the said contact points 38 and 39.

10 Referring now to the means whereby the mechanism is electrically operated, the reference numeral 41 denotes one of the gear wheels located in the clock-work mechanism, which completes a full rotative movement in a predetermined interval of time. In the 15 present instance I prefer to utilize a gear wheel which will complete its revolution in a relative short period;—for instance a period of half an hour.

15 Mounted upon the wheel 41, near the periphery thereof, is a post 42. Pivotedly mounted upon the frame 3 at 42, is a contact arm 44, the outer end of which lies in the path of the post 42, so that said post will engage said arm during the rotative movement of the gear wheel 41. The contact arm 44 is provided with a contact member 45, which co-operates with an opposed contact member 46, carried upon a spring 47, the latter being mounted upon the insulating block 48, which is carried upon the frame 3. A spring 49 connected with the arm 44 normally holds the latter in engagement with a fixed stop or abutment 50. By means of the construction just described, it will be noted 20 that when the gear wheel 41 completes a rotative movement it will engage with the arm 44, thereby swinging the same and causing the contact member 45 thereof to engage with the contact member 46 of the spring 47, and that such engagement will continue until the post 42 has been carried far enough to permit it to slip over the end of the contact member 44, spring 47 meanwhile yielding to permit of continued rotation of the gear 25 wheel 41.

25 Leading from the spring 47 and electrically connected therewith, is a wire 51, which is connected with a source of electrical supply 52, which may be an ordinary dry cell battery. A wire 53 connects the opposite side of the battery with one terminal 54 of the electromagnets 27, the opposite terminal 55 of which is connected as by means of the wire 56 with the contact member 38.

30 It will be noted that the frame 40, which carries the contact point 39, is grounded to the mechanism of the clock, and that the arm 44, which co-operates with the post 42, upon the gear wheel 41, is likewise grounded 35 to the mechanism of the clock. Thus it will

be seen that when the post 42 swings the arm 44 to engage the contact members 45 and 46, the following circuit will be completed:

Through the spring 47, wire 51 to battery, from battery to the wire 53, through the electromagnets 27, then through the wire 56, from contact member 38, then through the arm 40, through its grounded connection with the mechanism, back to the arm 44.

35 Figure 2 of the drawings shows the parts in normal position, that is to say, the free end of the spring 34 lies in engagement with an insulating block 57, carried by the wheel or disk 33.

The closing of the circuit next above described will cause the electromagnets 27 to vibrate the armature 24, thereby opening and closing the circuit between the contact points 38 and 39, whereby the lever 15 will be vibrated, and causing the pawl 16 thereof to rotate the ratchet wheel 14. This vibratory movement will continue until the post 42 of the gear wheel 41 has disengaged itself from the arm 44. Before this occurs, however, the wheel or disk 33 will have been rotated a sufficient amount to carry the end of the contact spring 34 from engagement with the insulating block 57 and in engagement with the periphery of the wheel 33, whereby the following circuit will be closed:

40 Through the spring member 34, the wire 58, wire 51 to battery, then through the wire 53 to terminal 54 of the electromagnets, then through terminal 55 of said magnets through the wire 56 to the contact member 38, then through the contact arm 40 to ground, and back through ground to the contact spring 34.

45 The closing of this last named circuit will, by means of the electromagnets 27, continue the vibratory movement of the armatures 24 until the wheel or disk 33 has been rotated to a sufficient extent to again engage the end of the contact spring 34 to the insulating block 57.

50 Thus it will be seen that the winding mechanism is initially operated by the closing of the circuit between the contact points 45 and 46, and that said circuit is closed for a sufficient time to permit the wheel 33 to be rotated to a sufficient distance to permit the closing of the circuit between said wheel and the contact spring 34, and that thereafter the circuit will be continually closed until the wheel 33 has completed its revolution, and the circuit again opened by the engagement of the contact spring 34 with the insulating block 57.

55 It will accordingly be seen that I have provided a construction adapted to attain, among others, all the ends and objects above pointed out, in an extremely simple yet efficient manner, and whereby the clock will automatically re-wind itself at predetermined intervals, insuring an even tension of the 130

main spring. By reason of the fact that the armature has no positive engagement with the end of the core, the re-winding operation is substantially noiseless. It will be understood that in accordance with the present construction the armatures 24, when the electro-magnets are de-energized, fall to their normal position by gravity. Springs may be utilized in this connection, if desired.

10 As many changes could be made in this construction without departing from the scope of the following claim, it is intended that all matter contained in the above description or shown in the accompanying 15 drawing shall be interpreted as illustrative only and not in a limiting sense.

Having thus described my invention what I claim as new and desire to secure by Letters Patent is:

20 In a clock, the combination of a train of gearing, a spring mounted on a shaft to operate said train, an electromagnet, a pair of circuits through a source of electrical energy connected to said electromagnet, an

armature for said electro-magnet, a ratchet 25 wheel to rotate said shaft to wind said spring, a pawl actuated by said armature through linkage to rotate said ratchet wheel, a circuit breaker for said circuits actuated by the movement of said armature to the attracted position, a spring held arm operable by a gear of said train to connect said source of energy to said electromagnet, and to break said connection by the rotation of said gear upon partial winding of said spring, 30 and a disc mounted upon said shaft, means to contact with said disc to maintain the connection of said electromagnet with said source of power through the other of said circuits to complete said winding, and means 35 to cause said first named means to be made ineffective upon completion of said winding.

In testimony whereof I affix my signature in the presence of two witnesses.

CHARLES E. BOILLOT.
